E. C. KILLEBREW

VACUUM CLEANER

Filed Nov. 19, 1926

Fig. 2. Inventor: Ernest Coral Killebrew
By M. N. Hendon Atty.

UNITED STATES PATENT OFFICE.

ERNEST CORAL KILLEBREW, OF EVANSVILLE, INDIANA.

VACUUM CLEANER.

Application filed November 19, 1926. Serial No. 149,370.

The object of my invention is to provide a vacuum cleaner having improved means by which a beating action may be obtained in addition to the usual vacuum or suction action.

The improvements reside in the provision of either a flexible cord, strip or piece, however constructed and mounted, which will be operably connected to the motor in an improved manner enabling different adjustments to be had to effect changes in the beating action.

My invention supplies means for effectually agitating the carpet, rug, fabric, or the like which is being subjected to vacuum action, thereby loosening the dust and particles of dirt, lint, etc. which ordinary vacuum action will not properly remove.

The beating or whipping action which is obtained by the use of my improvements, can be regulated as to stroke by the improved means I have provided for that purpose.

Further improvements consists of short and long handles, the short handle being permanently attached to the vacuum cleaner and enabling the latter to be readily pushed around in places where space is limited; the other handle being detachably connected to the vacuum cleaner so that it may be removed when not needed and being of suitable length so that the user may push the vacuum cleaner across the floor when a floor covering, or a floor is being treated.

There are many uses to which my vacuum cleaner may be put, such as cleaning carpets and upholstery in automobiles, cleaning upholstered furniture, etc, as with my improvements, the short handle is not in the way when the vacuum cleaner is used on a floor or floor covering, but the long, pushing handle may be removed when the vacuum cleaner has to be used in close quarters.

Other features of the invention reside in a closure arranged to enable the user to readily insert the fingers into the casing or shell for the purpose of adjusting the means for operating the beater, and other details of construction appear more fully herein-after.

In the accompanying drawings:

Figure 1, is a side elevation, the shell or

casing being in section and both handles being provided;

Fig. 2, is a bottom view;

Fig. 3, is a cross-section through the shell or casing; and

Fig. 4, is a detail view, partly in section, showing the adjustable crank pin and the latch therefor.

The shell of the electric motor appears at 1 and the usual suction fan is shown at 2, said fan drawing in the dirt, lint, and other material through an opening 3 and forcing it through housing 4 into the usual bag or container 5 which is removably attached to conduit 6.

The nozzle or suction mouth is shown at 7 and is provided with a screw closure 8 which screws into an opening 9 which is of sufficient size to permit the introduction of the fingers of the user for the purpose of effecting adjustments of parts presently to be described.

The vacuum cleaner is supported by a frame 10 preferably hinged at 11 to the housing 4 of said frame having a roller 12 adapted to travel on the floor or rug or other surface over which the vacuum cleaner is being pushed. A rest 13, carried by the frame 10 supports the motor shell 1. A short handle 14 attached to the frame 10, is adapted for use in pushing and pulling the vacuum cleaner about when it is to be used in small spaces or small quarters as, for instance, when cleaning the carpets, or upholstery, of automobiles, or upholstery of chairs, sofas, etc.

This handle is so short that it is not in the way when the vacuum cleaner is being pushed over a floor or rug but it is always handy when the vacuum cleaner is to be used in the manner previously described.

The usual type of handle 15 is employed for pushing and pulling the vacuum cleaner over floors, rugs, carpets, etc, said handle being connected to the sides of the motor casing 1 at 16 in a manner enabling it to be detached whenever it is desired to use the vacuum cleaner in close quarters. The handle 14 may then be used for manipulating the cleaner.

Instead of using a rotary brush or similar device for loosening the dust, dirt, and

other matter which is to be removed from the surface treated by the vacuum cleaner, as has previously been proposed, I have devised an improved beating or agitating device, adapted to be set to perform different movements or operations. This comprises a cord, bar, or piece or pieces 17 which is anchored at 18 to the nozzle 7 as, for instance, by the detachably connected plates shown. 10 This enables the beating or agitating device to be removed and another substituted when desirable or necessary.

This beating or agitating device may be an elastic or rubber cord or piece of elastic fabric, or a flexible or resilient piece or pieces of metal. The beating device in question is rapidly vibrated up and down through many paths, inasmuch as the motor shaft 19 which operates it, revolves at a high rate of speed, 20 said shaft being the armature shaft for the motor 1 and also carrying the suction fan 2.

I am aware that various mechanical movements may be interposed between the beating device 17 and the shaft 19 and my invention, in its broadest aspect, is not limited to any specific operative connection, for the beating device 17.

I prefer, however, to provide the simple and effective improved operating connection 30 shown and now to be described. This consists of a crank arm 20 carried by the shaft 19 and rotated by it, a crank pin 21 carried by said crank arm 20, and a connecting rod 22, said connecting rod being attached in 35 any suitable operative manner to the beating device, as shown at 23. The beating device 17 may have an eyelet to which the connecting rod is attached. Without intending to limit the invention, it may be said that 40 considerable modification can be resorted to in providing the beating device 17.

The crank pin 21 is made adjustable to different angles so that the cycles or paths of movement of the sweeping device 17 may 45 be changed, at the will of the operator. One arrangement for setting the crank pin 21 to different positions is shown in Fig. 4 where the crank pin is pivotally connected at 24 to the crank arm 20. A latch 25, carried by

50 crank arm 20 is adapted to engage with any one of a series of notches 26 on the hub of the crank pin 21.

By removing the closure 8, the user can insert the fingers through the hole 9 and release the latch 25 and set the crank pin 21 55 to another position, when desired.

The whipping action of the device 17 loosens the dust, dirt, and other particles 60 from the surface being cleaned and insures thorough cleansing.

What I claim is:

1. In a vacuum cleaner provided with a motor, a motor shaft, and a nozzle having a suction mouth, an elongated, flexible beating device whose end parts are connected to the 65 suction mouth and whose intermediate part is free to vibrate within said suction mouth, a crank on the motor shaft, and a rod connecting said crank and said intermediate part of the beating device. 70

2. In a vacuum cleaner provided with a motor, a motor shaft, and a nozzle having a suction mouth, an elongated, flexible beating device whose end parts are connected to the 75 suction mouth and whose intermediate part is free to vibrate within said suction mouth, a crank arm on the motor shaft, a rod connected to said intermediate part of the beating device, and an adjustable connection between the rod and the crank arm whereby 80 the throw of said connecting rod may be changed.

3. In a vacuum cleaner provided with a motor, a motor shaft, and a nozzle having a suction mouth, an elongated, flexible beating device whose end parts are connected to the 85 suction mouth and whose intermediate part is free to vibrate within said suction mouth, a crank arm on the motor shaft, a rod connected to said intermediate part of the 90 beating device, and a crank pin carried by the crank arm which is adjustable in relation to said crank arm, said rod being connected to said crank pin, and means for locking said pin in adjusted position. 95

In testimony whereof I affix my signature.

ERNEST CORAL KILLEBREW.
